UNITED STATES PATENT OFFICE.

HENRY H. MERCER, OF CLAREMONT, NEW HAMPSHIRE, ASSIGNOR TO THE SULLIVAN MACHINERY COMPANY, OF SAME PLACE AND CHICAGO, ILLINOIS.

CUTTING-CHAIN FOR MINING-MACHINES.

SPECIFICATION forming part of Letters Patent No. 659,348, dated October 9, 1900.

Application filed March 9, 1899. Serial No. 708,351. (No model.)

To all whom it may concern:

Be it known that I, HENRY H. MERCER, a resident of Claremont, in the county of Sullivan and State of New Hampshire, have invented a new and useful Improvement in Cutter-Chains for Mining-Machines; and I do hereby declare the following to be a full, clear, and exact description thereof.

My invention relates to cutter-chains to be used in connection with mining-machines.

The object of my invention is to adapt an ordinary cable-chain composed of welded links for use in connection with mining-machines by arranging the cutters thereon in such a manner as to provide a strong and durable cutter-chain.

To this end my invention comprises, generally stated, an ordinary cable-chain with cutters arranged thereon and means for retaining said cutters securely in position theron, all of which will be fully hereinafter set forth and claimed.

To enable others skilled in the art to make and use my invention, I will describe the same more fully, referring to the accompanying drawings, in which—

Figure 1 is a top view of a portion of a chain with the cutters secured thereto. Fig. 2 is a view of a portion of a chain with one-half of the block and holding device for cutters removed. Fig. 3 is an end view of one of the blocks with the cutters secured therein. Fig. 4 is a side view of a block and a portion of chain with cutters in position. Fig. 5 is a view of bolt for holding cutters in place. Fig. 6 is a top view of a portion of a chain, showing a modified form of construction. Fig. 7 is an edge view of same. Fig. 8 is a top view where the cutters are secured in seats in the outer faces of the blocks. Fig. 9 is a sectional view of same. Fig. 10 is an edge view. Fig. 11 is a view of raker-cutter. Fig. 12 is a view of cam-pin.

Like letters of reference indicate like parts in each view.

The letter *a* designates an ordinary cable-chain or section of cable-chain composed of welded links connected in the customary way.

Arranged at suitable intervals on said chain *a* are the blocks *b*, said blocks being formed

of sections *b'* *b''*, secured together by rivets *c* or in any other suitable manner.

The sections *b'* *b''* have seats *d* formed on their inner contiguous faces which coincide with each other, so as to receive the links of the chain. As shown in Fig. 2, the central link *a'* is held between the sections *b'* *b''* of the block *b*, as well as the adjoining ends of the links *a''* *a'''*, said links fitting in said seats *d*. As the chain is continuous through the block and only a small portion of the metal is cut away to receive the links of the chain the strain does not come on the rivets *c*, but only on the links of the chain. The rivets *c* only act to hold the blocks on the chain. By this construction the blocks may be removed without disconnecting the links of the chain in case it is desired to remove a broken or worn out block and replace it by a new one.

The sections *b'* *b''* of the blocks have dovetailed or other suitable seats *e* formed on their outer faces, said sections having the extensions *f*, which increase the length of the seats *e* and permit of a longer cutter being employed. Said extensions are also adapted to engage with the upper and lower face of the cutter-bar and prevent the chain from rising or lowering when in use.

Fitting in the seats *e* are the cutters *h*, with the beveled edges *h'*. These cutters are held rigidly in the seats *e* by means of the bolts *i*, which pass through the sections *b'* *b''* of the block. These bolts *i* have the niche or hook *i'* at one end adapted to engage the cutters *h* on one side, and when the nuts *i''* on said bolts are tightened the hooked end of the bolt is drawn up tight against the cutter and locks it securely within the seat *e*. By this construction the cutters are held securely in place, and they project out from the outer faces of the blocks, so that they make a smooth even cut in the coal.

Other forms of blocks and cutters may be employed, as well as different devices for holding the cutters in place, without affecting the spirit of my invention.

In Figs. 6 and 7 the invention is illustrated in connection with a cutter-block adapted to support what may be termed a "raker-cutter." This cutter is arranged to project from

the block at about its center or adjacent thereto, so as to break down and carry out the coal which remains after the outside cutters—such as shown in Figs. 8, 9, and 10—have made the upper and lower cut. The letter *k* designates a cable-chain of any suitable construction, the adjacent links *k' k²* of said chain being connected to the cutter-block *m*, which is interposed between said links. This cutter-block is formed of a solid piece of metal, and said block has the seats *n* at each end thereof adapted to receive the ends of the links *k' k²*. Rivets *o* pass down through openings in said block and through the said links and act to secure the block *m* firmly to the links *k' k²*. The block *m* is also provided with one or more seats or recesses *q*, within which the tailpieces *r'* of the cutters *r* fit. A pin *s*, with niches *s'* formed therein, passes down through said block *m*, said niches coinciding with the niches *t* in the cutters *r* when said pin is inserted. By turning the pin the cutters are firmly secured within the seats *q*. The pin *s* has a head on one end and the other end is riveted, as at *s²*. A spring-washer *s³* is interposed between the portion *s²* and the block, so as to prevent said pin from turning or working loose. This manner of securing the cutters in place, however, forms no part of my invention, but is part of an invention of J. L. Mitchell, for which he filed an application for patent on the 7th day of March, 1899, Serial No. 708,084.

In Figs. 8, 9, and 10 the cutter-block is adapted to support cutters on its outer faces. These blocks *u* are also formed of a solid piece of metal, with seats *u'* formed therein to receive the links *k' k²*. Rivets *v* secure the links to the blocks *u*.

Formed in the outer faces of the block *u* are the dovetailed seats *w*, adapted to receive the cutters *x*. These cutters are held in the seats *w* by means of the bolts *y*, which pass through the block *u*, the inner ends of said bolts having the hooked portions *y'*, adapted to engage the cutters *x* on one side, so that when the nuts *y²* on said bolts are tightened the cutters are clamped rigidly within their seats, the same as above.

By my invention I provide a very simple

and economical form of cutter-chain, one which will be strong and durable and in which the cutter-blocks can be arranged at suitable intervals on an ordinary cable-chain, so that they may be easily removed and others substituted therefor, as may be desired.

What I claim as my invention, and desire to secure by Letters Patent, is—

1. In a chain-cutter for mining-machines, a cable-chain composed of welded links, a block on said chain, and a cutter carried by said block, substantially as set forth. 60
2. In a chain-cutter for mining-machines, a cable-chain composed of welded links, a block engaging said chain and detachably secured thereto, and a cutter carried by said block, substantially as set forth. 65
3. In a chain-cutter for mining-machines, an endless cable-chain composed of welded links, a sectional block engaging the links of said chain and secured thereto, and a cutter carried by said block, substantially as set forth. 70
4. In a chain-cutter for mining-machines, an endless cable-chain composed of welded links, a block composed of sections having seats on their contiguous faces conforming to the links and adapted to receive the same and secured thereto, and a cutter carried by said block, substantially as set forth. 75
5. In a chain-cutter for mining-machines, an endless cable-chain composed of welded links, a block composed of sections adapted to engage the links of said chain and secured thereon, and a cutter extending out from each 80 of said sections, substantially as set forth.
6. In a chain-cutter for mining-machines, an endless cable-chain composed of welded links, a block composed of sections adapted to engage the links of said chain and secured 85 thereon, said sections having seats formed in their outer surfaces, and cutters fitting in said seats, substantially as set forth.

In testimony whereof I, the said HENRY H. MERCER, have hereunto set my hand.

HENRY H. MERCER.
